UNITED STATES PATENT OFFICE.

JOHN J. BRAZNELL, OF ST. LOUIS, MISSOURI.

DEVICE FOR CLEANING AND REFILLING DIPPING-TANKS.

No. 824,973.

Specification of Letters Patent.

Patented July 3, 1906.

Application filed November 10, 1905. Serial No. 286,757.

To all whom it may concern:

Be it known that I, JOHN J. BRAZNELL, a citizen of the United States, residing at the city of St. Louis, in the State of Missouri, have invented a new and useful Improvement in a Device for Cleaning and Refilling Dipping-Tanks, of which the following is a specification.

My invention relates to a device for cleansing enamels, paints, and other liquids used upon metal bedsteads, furniture, &c. The tank in which the liquid is kept becomes filled with dirt and sediment of various kinds, and it is necessary to empty and clean out the dipping-tank and also filter the liquids and then return them to the tank. The ordinary manner of doing this—that is, by dipping or pouring out the liquid, cleaning the tanks out, passing the liquid through a strainer, and then pouring it back into the tanks—consumes considerable time and labor, especially in a large factory.

The object of this invention is to save time and labor by drawing the liquid from the dipping-tank by means of a suction-pump and passing it back to the tank through a filter, thus straining the liquid, keeping it agitated, and also not exposing it unnecessarily to the action of the air, which is injurious to the enamel.

The invention consists in the novel features of construction hereinafter described, pointed out in the claim, and shown in the accompanying drawings, in which I have shown, partly in side elevation and partly in section, the simplest form of my invention.

In the drawings, A represents a suitable table or platform having an opening through which the body portion of a tank B can be passed, and upon the platform A is found a suitable suction-pump, which I have shown as belonging to the hand-operated type. Suitable pipes D and E connect the pump and the lower portion of the tank B, the pipes E and D being connected by a four-way coupling provided with screw-plugs F. A tank G is located at any desired point above the level or top of the tank B and is supported in any desired manner.

A pipe E' leads from the suction-pump C and is connected by a four-way coupling to a pipe H, which extends horizontally to a point above the tank G, and a depending pipe H' is also connected by a four-way coupling to the

pipe H. The pipe H' opens downwardly into the tank G. From the bottom of the tank G depends the pipe J, also connected by a four-way coupling to the pipe J', which discharges into the upper portion of the tank B. All of the four-way couplings mentioned are provided with screw-plugs F and by removing these plugs all of the pipes may be cleaned.

In the tank G is hung a bag or sack K in alinement with the pipe H', and this bag is supported within the tank G by suitable hooks K', a space being left between the sides of the bag and the sides of the tank G and the top of the bag and below the level of the top of the tank G.

The operation of the device is as follows: The dipping-tank to be cleaned having first been placed in position and connected to the pipe D, the pump C is started, and the liquid will be passed through the pipes D, E, E', H, and H' and discharged into the bag K. This bag may be a close-woven sack, if the liquid is thin, or a loosely-woven one for liquids of a heavy body. The filtered liquid passes through the pipes J and J' and is discharged back into its proper tank B. Should the sack or bag K become clogged, the liquid will not run over upon the floor, as the top of the sack is below the top of the tank G and is spaced from the sides of it, so that the liquid is free to pass around the sides of the tank G to the pipe J when the sack overflows. By means of this construction damage to the floor and loss of liquid is prevented should the attendant neglect to change the sacks when one has been clogged with dirt and foreign substances.

This device not only cleanses and filters the liquid and removes the dirt and sediment from the dipping-tank, but also agitates and keeps the liquid well mixed.

Having thus fully described my invention, what I claim as new, and desire to secure by Letters Patent, is—

A device comprising a dipping-tank, a filter-tank arranged in a higher level than the dipping-tank, pipes leading from the bottom of the dipping-tank to a point above the filtering-tank and discharging therein, and a filter placed in the filtering-tank, and spaced from the sides of the said tank.

JOHN J. BRAZNELL.
